United States Patent Office

Des. 215,807
Patented Nov. 4, 1969

215,807

BOTTLE OPENER

Wilfred W. Weingardt, 5247 Southeastern Ave.,
Indianapolis, Ind. 46203

Filed Mar. 7, 1969, Ser. No. 16,114

Term of patent 14 years

Int. Cl. D8—02

U.S. Cl. D8—40

Fig. 1

Fig. 2

Fig. 3

Fig. 4

FIG. 1 is a perspective view of a bottle opener showing my new design;

FIG. 2 is a top plan view thereof;

FIG. 3 is a perspective view of a bottle opener showing another form of my new design wherein a pivoting ring member is provided as shown; and

FIG. 4 is a top plan view thereof.

I claim:

The ornamental design for a bottle opener, as shown and described.
